UNITED STATES PATENT OFFICE.

EDWIN F. BEUGLER, OF BUFFALO, NEW YORK, ASSIGNOR TO E. & B. HOLMES MACHINERY CO., OF BUFFALO, NEW YORK, A CORPORATION OF NEW YORK.

BARREL-REVERSING MECHANISM.

Application filed July 12, 1924. Serial No. 725,748.

This invention relates to a machine for reversing end for end barrels while the same are mounted in an apparatus which is adapted to apply heads to opposite ends of the barrel, which machines in the cooping art are known as heading-up machines.

It is the object of this invention to provide a machine for this purpose which is comparatively simple in construction, which 10 can be easily and conveniently operated and which permits of quickly reversing a barrel end for end and maintaining the same reliably in position with reference to other parts of a heading-up machine which operate to 15 apply heads successively to opposite ends of the barrel.

In the accompanying drawings

Figure 1 is a perspective view of a barrel reversing mechanism embodying my invention 20 and showing the parts in their retracted or inoperative position preparatory to engaging opposite sides of the bilge of a barrel which is mounted on the support of a heading-up machine.

Figure 2 is a similar view showing the 25 position of the parts when the jaws of the reversing mechanism are engaged with opposite sides of a barrel and the latter has been elevated and turned part way in the operation of reversing the same, end for end.

Figure 3 is a fragmentary top plan view of this reversing mechanism showing the 30 parts in the position corresponding to Figure 1 and Figure 4 is a fragmentary vertical transverse section, taken on line 4—4 of Fig. 3 and looking forwardly.

Figure 5 is a fragmentary vertical section taken on the correspondingly numbered line 35 in Fig. 4, and

Figure 6 is a sectional view taken on line 40 6—6, Fig. 3 on an enlarged scale of one of the grippers, jaws or chucks adapted to engage with one side of the barrel for pivotally supporting the same while being 45 reversed.

Similar characters of reference indicate like parts in the several figures.

The numeral 10 represents the main frame 50 or base portion of the machine which is adapted to rest upon the floor of the building and provided centrally with a table 11 upon which opposite ends of the barrel 12 are adapted to rest while heads are being successively applied to these ends by the

heading-up mechanism of the barrel making 55 machine. This heading-up mechanism may be variously constructed but as the same forms no part of the present invention no detailed description of the same is deemed necessary. As an instance of a machine of 60 this character attention is directed to that shown in U. S. Patent No. 946,714 dated January 18, 1910 and also the machine shown in the pending application, Serial No. 685,286 filed January 9, 1924.

The reversing mechanism whereby the 65 barrel is reversed end for end so that its two ends may be supported successively on the table or platform 11 and which, according to the most approved organization of my 70 invention, is constructed as follows:

The numeral 13 represents a horizontal rock shaft which is arranged transversely in front of the barrel support and journaled in bearings 14 on the front part of the main 75 frame or base. On opposite sides of the barrel support are arranged two longitudinal lifting arms 15, each of which is mounted loosely at its front end on the rock shaft 13 adjacent to the outer side of one of the bearings 14 so that this lifting arm turns about the same axis as the shaft but the arm 15 is capable of turning with the shaft 13 and the shaft and arm are also capable of turning independently of each other. In the rear 80 of the lifting arms and arranged on transversely opposite sides of the barrel support are two upright gripper arms 16 each of which is pivotally connected at its lower end with the rear end of one of the lifting arms 85 by means of a pivot pin, screw or bolt 17 arranged horizontally and lengthwise relatively to the machine and passing through the lower part of the respective gripper arm and into the rear end of the companion lifting arm 15.

Upon the upper ends of the two gripper arms are arranged two jaws or chucks, which are adapted to engage with diametrically opposite sides of the bilge portion of 100 the barrel in a direction transversely of the machine. Each of these jaws comprises a head 18 which is adapted to engage with a part of the barrel body and which is pivotally connected with the rear end of one of the adjusting rods 23 in such manner that the head is capable of swiveling on this rod 105 and thus adapt itself to varying angular

positions of the surface of the barrel relative to this rod. The first construction of the front face of the supporting head is constructed in the form of a rubber pad 19 which is connected with the head by means of an under-cut boss 50 arranged on the front side of the head and engaging with an under-cut recess 51 on the back of the pad, the latter being provided on its front side with a plurality of projections 52 in order to enable the same to obtain a firm frictional grip on the side of the barrel. The pivotal connection between the gripper head and the rod 23 is preferably effected by providing the rear side of the head with a recess having reduced inner part 53 which terminates in a ball race 54 and an enlarged outer part 55. The front part of the adjacent rod 23 projects into this recess of the gripper head and is provided at its inner end with a ball race 56 between which and the ball race 54 on the bottom of this recess an annular row of balls 57 is arranged, while that part of this rod within the enlarged part 55 of the recess is spaced therefrom circumferentially. By means of this construction the gripper head is journaled on the gripper rod 23 so as to rotate freely thereon and permit the barrel to be easily reversed while at the same time the gripper head is free to rock or swivel in all directions and thus adapt the face of this gripper head to the varying positions which the surface of the barrel may occupy relative to the rod 23. In order to prevent the gripper head from being moved lengthwise from the rod 23 and still permit of free rotation and swiveling motion of head on this rod a connection is provided between these parts which preferably consists of the cotter pin 58 passing transversely through the gripper head and engaging with an annular groove 59 on the periphery of the rod 23 in rear of the ball race 56 thereof.

Means are provided for adjustingly mounting each of these jaws on the upper part of one of the gripper arms so as to adapt these jaws to barrels of different width and diameter. The preferred means for this purpose which are shown in the drawings comprise a bracket 20 engaging with the rear side of the upper part of each gripper arm and provided with a horizontal transverse sleeve 21 on a separate part and a vertical slit 22 in its lower part extending from the under side of the bore of said sleeve to the lower end of said bracket, the horizontal transverse adjusting rod 23 arranged in the sleeve 21 and carrying at its inner end the head 18 of one of the jaws and a clamping bolt 24 passing through the lower split parts of the bracket and through an upright slot 25 in the upper part of the respective gripper arm, as best shown in Figs. 4 and 5. Upon loosening the clamp-

ing bolt 24 the adjusting rod 23 can be moved horizontally in the sleeve 21 of the bracket for the purpose of adapting the respective jaw to the diameter of the barrel which is to be reversed. By raising and lowering this bracket on the gripper arm, which is permissible by sliding the bolt 24 in the slot 25, the gripper jaw can be raised or lowered to suit the height or length of the barrel which is being coopered and by tightening the clamping bolt 24 the split parts of the bracket are closed or drawn together so as to grip the adjusting rod 23 in the sleeve 21 and at the same time this bracket is drawn tightly against the rear side of the respective gripper arm, thereby holding the parts in their adjusted positions.

The downward movement of the lifting arms and the parts mounted thereon is effected by gravity but if desired this may be aided by spring pressure, as for example by means of a spring 26 connected at its rear end with a fixed part 27 of the base while its front end is connected with a lug 28 projecting inwardly and upwardly from one of the lifting arms 15, as shown in Figs. 1 to 4.

The gripper arms are yieldingly held in a position in which their upper or jaw carrying ends are moved apart and away from opposite sides of the barrel when the same are in their lowered position, this being preferably effected by the following means.

The numeral 29 represents lugs projecting laterally inward from the lower parts of the gripper arms and each having its inner part overhanging the adjacent part of the base and provided on its underside with a downwardly open pocket 30. Within the pocket of each lug 29 is arranged a buffer spring 31 which engages its upper end with the bottom of this pocket. Extending downwardly through the bottom of this lug and the spring therein is a buffer rod 32 which has a shoulder 33 at its upper end adapted to bear against the upper side of the lug 29 while its lower end is adapted to bear against the adjacent part of the base and is provided with a shoulder 34 engaging with the lower end of the buffer spring 31. These shoulders are preferably formed on this rod by constructing the same in the form of a bolt, the head of which forms the upper shoulder 33 and the nut of which forms the lower shoulder 34. Upon moving each of the gripper arms downwardly the adjusting rod or member 32 strikes the top of the base so that its further movement in this direction is arrested, thereby causing the gripper arm during its continued downward movement with the companion lifting arm to be swung outwardly at its upper end and thereby disengage the jaw or gripper on this gripper arm from the periphery of the bar-

rel. This released position of the grippers or jaws from the barrel is indicated by full lines in Figs. 1, 3 and 4.

For the purpose of moving the upper ends 5 of the gripper arms inwardly and engaging the jaws thereof with opposite sides of the barrel so that the latter is gripped thereby, means are provided which in their preferred form are constructed as follows:

10 The numerals 35 are two vertically swinging shifting arms which are secured at their front ends to the rock shaft 13 adjacent to the outer sides of the hubs of the lifting levers 15 and each provided at its rear end 15 with a tappet 36 which preferably has the form of a roller pivoted on the extremity of the respective shifting arm in any suitable manner. Each of these tappets engage with a cam face 37 which is formed on the lower 20 part of the outer edge of each gripper arm. At the lower and upper extremities of the cam face 37 of each gripper arm the latter is provided with lower and upper stops 38, 39, which limit the vertical motion of the respective tappet which co-operates with this 25 cam. On one part of the rock shaft 13, preferably the right hand end thereof, the same is provided with a forwardly projecting treadle 40 on which the operator of the 30 machine is adapted to step. The outward swinging movement of each gripper arm away from the side of the barrel is limited by engagement of a stop 41 arranged on the outer part of this gripper arm below the 35 pivot 17 and engaging with a corresponding stop 42 on the adjacent part of the rear end of the companion lifting arm, as shown in Figs. 1 and 4.

While this spring mechanism is at rest 40 and the parts are in a retracted position which leaves the top of the supporting table or platform free to place an unfinished barrel on the platform or remove a finished barrel therefrom, the lifting levers are in their depressed position, the gripper arms are moved to their outmost position, the gripper jaws are disengaged from opposite sides of the barrel, the shifting arms are lowered and their tappets are in engagement 45 with the lowermost parts of the cam faces 37 and the pedal 40 is in its elevated position, as shown in Figs. 1 and 4.

After the attendant has placed a barrel 50 in its operative position in which one of its ends engages with the top of the table or platform 11 the heading-up machine is first operated for applying a head to the upper end of the barrel. Thereafter the operator 55 steps on the treadle 40 preliminary to effecting a reversal of the barrel end for end. During the first part of this downward motion of the treadle 40 the shifting arms 35 are raised and their tappets 36 are caused 60 to move upwardly along the cam faces 37 of the gripper arms whereby the latter are

moved inwardly or toward each other and the grippers or jaws thereon are caused to engage with opposite sides of the central or bilge portion of the barrel body. After the gripper arms have been moved inwardly to 65 such an extent during the first part of the downward movement of the treadle as will produce a firm engagement of the jaws with the opposite sides of the barrel then the continued downward movement of the treadle 70 will cause the shifting arms 35 to produce a lifting effect upon the gripper arms and lifting arms whereby the barrel will be lifted with its lowered end out of engagement from the top of the supporting table 75 or platform 11. The raising of the barrel at this time is only sufficient to permit the barrel to be turned by the operator about the horizontal transverse axis of the rubber pad 19 which is arranged axially in line for this purpose. A partial turning end for 80 end of the barrel by the operator is represented in Fig. 2 and when this turning has been completed so that the end of the barrel which formerly was uppermost is now lowermost, then the attendant removes his foot pressure from the treadle 40 so as to allow the barrel to descend by gravity together with the gripping and elevating mechanism 85 associated therewith. The barrel is arrested in its downward movement and engages its lower end with the table or platform during the first part of the downward motion of the lifting arms and shifting arms, and during the last part of the downward motion of the lifting arms and the gripper arms the buffer mechanism on the gripper arms engage with the top of the base so that the gripper arms at this time are caused 90 to turn on the lifting arms and move their jaws outwardly out of engagement from opposite sides of the barrel. This outer movement of the gripper arms relatively to the barrel body and the descent of the lifting arms is limited by engagement of the stops 95 41 on the gripper arms with the stops 42 on the lifting arms, as shown in Fig. 4. The downward movement of the shifting arms is limited by engagement of their tappets 36 with the lower stops 38. In the event that the shaft 13 is rocked by the depression of the pedal 40 when no barrel is present on the platform excess inward throw and possible displacement of the gripper arms is prevented by engagement of the tappets 36 with the upper stops 39 of the gripper arms. 100

Owing to the fact that a single depression of the treadle 40 of this mechanism will produce a gripping and centering of the barrel as well as a lifting effect of the same from the platform the barrel is very easily and quickly placed in a position in which the operator can quickly and conveniently turn the barrel end for end on the rubber pad 105 110 115 120 125

19 and then can, by releasing the pressure on the treadle 40, as quickly lower the barrel on the platform and again disengage the reversing mechanism therefrom leaving 5 the barrel in the proper position to be operated upon the second time by the heading-up mechanism without requiring a second centering operation for this purpose.

This barrel reversing mechanism is very 10 rugged in construction and not liable to get out of order under the severe usage to which the same is likely to be subjected while in use and it is very effective in its operation of raising and lowering the barrel to permit of such reversal without requiring more than ordinary manual effort for this purpose, thereby materially increasing the output of the barrel making machine in connection with which the same is used.

20 I claim as my invention—

1. A barrel reversing mechanism comprising two rotatable jaws adapted to engage with opposite sides of a barrel, gripper arms which carry said jaws and which turn about 25 longitudinal horizontal axes, lifting arms which turn about a transverse horizontal axis and to which the gripper arms are pivoted and means for operating said arms and jaws simultaneously.

30 2. A barrel reversing mechanism comprising a horizontal support upon which the barrel to be reversed is adapted to rest, a horizontal rock shaft journaled transversely in front of said support, two lifting arms 35 arranged lengthwise on opposite sides of the barrel support and mounted at their front ends to said rock shaft, two upright gripper arms arranged on opposite sides of the support and each connected at its lower end 40 with the rear end of one of said lifting arms by a horizontal longitudinal pivot, gripper jaws mounted on the upper ends of said upright arms, and means for raising and lowering said lifting arms and moving said 45 gripper arms toward and from each other.

3. A barrel reversing mechanism comprising a horizontal support upon which the barrel to be reversed is adapted to rest, a horizontal rock shaft journaled transversely 50 in front of said support, two lifting arms arranged lengthwise on opposite sides of the barrel support and mounted at their front ends to said rock shaft, two upright gripper arms arranged on opposite sides of the support 55 and each connected at its lower end with the rear end of one of said lifting arms by a horizontal longitudinal pivot, gripper jaws mounted on the upper ends of said upright arms, and means for raising and 60 lowering said lifting arms and moving said gripper arms toward and from each other comprising a lifting pedal operatively associated with said lifting arms.

65 4. A barrel reversing mechanism comprising a horizontal support upon which the

barrel to be reversed is adapted to rest, a horizontal rock shaft journaled transversely in front of said support, two lifting arms arranged lengthwise on opposite sides of the barrel support and mounted at their 70 front ends to said rock shaft, two upright gripper arms arranged on opposite sides of the support and each connected at its lower end with the rear end of one of said lifting arms by a horizontal longitudinal pivot, 75 gripper jaws mounted on the upper ends of said upright arms and means for raising and lowering said lifting arms and moving said gripper arms toward and from each other comprising a lifting pedal operatively 80 associated with said lifting arms and a lowering spring connected with one of said lifting arms.

5. A barrel reversing mechanism comprising a horizontal support upon which the 85 barrel to be reversed is adapted to rest, a horizontal rock shaft journaled transversely in front of said support, two lifting arms arranged lengthwise on opposite sides of the barrel support and mounted at their front ends to said rock shaft, two upright gripper arms arranged on opposite sides of the support and each connected at its lower end with the rear end of one of said lifting 90 arms by a horizontal longitudinal pivot, gripper jaws movable toward and from opposite sides of said barrel, and means for adjustably connecting said jaws with said gripper arms.

6. A barrel reversing mechanism comprising a horizontal support upon which the barrel to be reversed is adapted to rest, a horizontal rock shaft journaled transversely in front of said support, two lifting arms arranged lengthwise on opposite sides of the barrel support and mounted at their front ends to said rock shaft, two upright gripper arms arranged on opposite sides of the support and each connected at its lower end with the rear end of one of said lifting arms 100 by a horizontal longitudinal pivot and each provided at its upper end with a vertical slot, a bracket engaging the upper part of each gripper arm and provided with a horizontal sleeve, an adjusting bolt passing through each bracket and the vertical slot of the respective gripper arm, a gripper rod adjustably arranged in each sleeve and provided with a jaw adapted to engage one side 110 of the barrel.

7. A barrel reversing mechanism comprising a base provided with a support upon which a barrel is adapted to rest, a horizontal rock shaft journaled transversely in front of said support, lifting arms arranged lengthwise on opposite sides of said support and mounted loosely at their front ends on said shaft, upright gripper arms arranged on opposite sides of said support and each connected at its lower end with the rear end of 120

115

120

- one of the lifting arms by a longitudinal horizontal pivot and provided with an upright cam surface, vertically movable shifting arms each having a tappet engaging one 5 of said cam surfaces for moving the respective gripper arm inwardly, and jaws arranged on said gripper arms and adapted to engage opposite sides of said barrel.
8. A barrel reversing mechanism comprising a base provided with a support upon which barrel is adapted to rest, a horizontal rock shaft journaled transversely in front of said support, lifting arms engaged lengthwise on opposite sides of said support and mounted loosely at their front ends on said shaft, upright gripper arms arranged on opposite sides of said support and each connected at its lower end with the rear end of one of the lifting arms by a longitudinal horizontal pivot and provided with an upright cam surface, vertically movable shifting arms each having a tappet engaging one of said cam surfaces for moving the respective gripper arm inwardly, jaws arranged on said gripper arms and adapted to engage opposite sides of said barrel, and means for moving said gripper arms outwardly.
9. A barrel reversing mechanism comprising a base provided with a support upon which a barrel is adapted to rest, a horizontal rock shaft journaled transversely in front of said support, lifting arms arranged lengthwise on opposite sides of said support and mounted loosely at their front ends on said shaft, upright gripper arms arranged on opposite sides of said support and each connected at its lower end with the rear end of one of the lifting arms by a longitudinal horizontal pivot and provided with an upright cam surface, and with shoulders at the upper and lower ends of said cam surfaces, vertically swinging shifting arms secured at their front ends to said shaft and provided at their rear ends with tappets engaging with said cam surfaces, gripper jaws mounted on the upper part of said gripper arms and adapted to engage with opposite sides of said barrel, a lug arranged on the lower part of each gripper arm and overhanging the base, a buffer spring mounted on each of said lugs, a buffer pin mounted on each of said lugs and interposed between the buffer spring thereon and said base a pedal connected with the shaft, and a spring connecting one of said gripper arms with one of said lifting arms.
11. A barrel reversing mechanism comprising a base provided with a support upon which a barrel is adapted to rest, a horizontal rock shaft journaled transversely in front of said support, lifting arms arranged lengthwise on opposite sides of said support and mounted loosely at their front ends on said shaft, upright gripper arms arranged on opposite sides of said support and each connected at its lower end with the rear end of one of the lifting arms by a longitudinal horizontal pivot and provided with an upright cam surface, and with shoulders at the upper and lower ends of said cam surfaces, vertically swinging shifting arms secured at their front ends to said shaft and provided at their rear ends with tappets engaging with said cam surfaces, gripper jaws mounted on the upper part of said gripper arms and adapted to engage with opposite sides of said barrel, a lug arranged on the lower part of each gripper arm and overhanging the base, a buffer spring mounted on each of said lugs, a buffer pin mounted on each of said lugs and interposed between the buffer spring thereon and said base a pedal connected with the shaft, a spring connecting one of said gripper arms with one of said lifting arms and means for limiting the outward movement of each gripper arm on its companion lifting arm.
12. A barrel reversing mechanism comprising a base provided with a support upon which a barrel is adapted to rest, a horizontal rock shaft journaled transversely in front of said support, lifting arms arranged lengthwise on opposite sides of said support and mounted loosely at their front ends on said shaft, upright gripper arms arranged on opposite sides of said support and each connected at its lower end with the rear end of one of the lifting arms by a longitudinal horizontal pivot and provided with an upright cam surface, and with shoulders at the upper and lower ends of said cam surfaces, vertically swinging shifting arms secured at their front ends to said shaft and provided at their rear ends with tappets engaging with said cam surfaces, gripper jaws mounted on the upper part of said gripper arms and adapted to engage with opposite sides of said barrel.
10. A barrel reversing mechanism comprising a base provided with a support upon which a barrel is adapted to rest, a horizontal rock shaft journaled transversely in front of said support, lifting arms arranged lengthwise on opposite sides of said support and mounted loosely at their front ends on said shaft, upright gripper arms arranged on opposite sides of said support and each connected at its lower end with the rear end of one of the lifting arms by a longitudinal horizontal pivot and provided with an upright cam surface, and with shoulders at the upper and lower ends of said cam surfaces, vertically swinging shifting arms secured at their front ends to said shaft and provided at their rear ends with tappets engaging with said cam surfaces, gripper jaws mounted on the upper part of said gripper arms and adapted to engage with opposite sides of said barrel.

sides of said barrel, a lug arranged on the lower part of each gripper arm and overhanging the base, a buffer spring mounted on each of said lugs, a buffer pin mounted on each of said lugs and interposed between the buffer spring thereon and said base a pedal connected with the shaft, a spring connecting one of said gripper arms with one of

said lifting arms and means for limiting the outward movement of each gripper arm on its companion lifting arm consisting of co-operating stops arranged on adjacent parts of each gripper arm and lifting arm. 10

In testimony whereof I affix my signature.

EDWIN F. BEUGLER.
